UNITED STATES PATENT OFFICE.

WILLIAM EDWARD LANE, OF WILMINGTON, NORTH CAROLINA.

ATTACHMENT FOR SUSPENDERS.

1,306,489.

Specification of Letters Patent. Patented June 10, 1919.

Application filed September 10, 1918. Serial No. 253,403.

To all whom it may concern:

Be it known that I, WILLIAM EDWARD LANE, a citizen of the United States, residing at Wilmington, in the county of New Hanover and State of North Carolina, have invented new and useful Improvements in Attachments for Suspenders, of which the following is a specification.

This invention relates to improvements in 10 suspenders for supporting men's trousers, and particularly to means for securing increased comfort and convenience in the use of garment supporters of this character.

It is the custom of many men to adjust the 15 suspenders so as to draw the trousers high to fit snugly about the seat and in the crotch. When the trousers are so adjusted and the wearer sits down a pulling strain is placed through the seat of the trousers upon the suspenders at the rear, causing the rear ends of 20 the suspender straps to be placed under undesirable tension. This results in discomfort to the wearer and the tendency of the straps to slide outwardly off the shoulders 25 of the wearer.

One object of my invention is to provide 30 simple, reliable and efficient means whereby the suspenders may be loosened at the front to give increased length to the suspender straps for the purpose of relieving the aforementioned strain and render the suspenders easy and comfortable to the wearer while he is sitting down, such means also serving to obviate any tendency of the suspender straps 35 sliding outwardly on the shoulders.

Another object of the invention is to provide means of the character and for the purpose described in the form of simple attachments to the cast-offs and front suspender ends, which attachments may be brought quickly and conveniently into use when desired for temporarily increasing the length of the suspender straps when the wearer is sitting down, without the necessity of changing 45 the normal adjustment of the suspenders, the construction being such that the attachments when in use will present a slight appearance and when not in use will be entirely or substantially concealed from view.

With these and other objects in view, the 50 invention consists of the features of construction, combination and arrangement of parts hereinafter fully described and claimed, reference being had to the accompanying drawing, in which:—

Figure 1 is a front view of the front end

of one of the suspender straps, showing the attachments in use for increasing the length of the strap.

Fig. 2 is a view of the same with the parts 60 separated from each other.

Fig. 3 is a longitudinal section through the parts shown in Fig. 1 with the parts of the suspender end arranged in normal position.

Referring to the drawing, 1 designates the forward end of one of the webs or straps of a pair of suspenders, having the back turned or looped extremity 2 for connection with the usual adjusting and clamping slide 70 3, whereby the length of said strap is adjusted. In the bight of this looped extremity 2 is held the suspending loop 4 to which is connected one end of the suspending tab 5 adapted to be folded over upon itself in 75 the usual manner to receive and hold the suspender end 6, which may be of any ordinary or preferred construction. The tab is provided with the usual snap fastener, consisting of the spring socket member 7, upon 80 its free end, to engage the spring stud 8, upon its secured end, to hold said tab in folded or looped form, whereby the suspender end 6 is detachably held in position.

In carrying my invention into practice I 85 provide a supplemental fastening member 9, shown in the present instance in the form of a hook, from which the suspended end 6 may be centrally suspended when the free end of the tab 5 is detached from the stud 8 and 90 allowed to hang down, as shown in Fig. 1. This hook is formed upon the free end of a plate 10 which, for convenience in applying it in position, may be formed at its opposite end with an opening or eye whereby it may 95 be fitted upon the shank of the spring eye 7 and secured or clamped thereby upon the tab 5. By this method of applying the supplemental fastening member 9 an ornamental connection is produced and the use of additional securing means obviated. When the eye 7 is disengaged from the stud 8 and the tab 5 allowed to hang down as described, and as particularly shown in Fig. 1, it will be evident that the effective length of the 105 strap 1 will be increased, so that upon connecting the suspender end 6 with and supporting it from the hook 9 sufficient slack will be allowed in the strap 1 to relieve any pull or tension which may fall 110 upon the strap when the wearer sits down. By loosening both tabs 5 upon the front

straps of the suspenders it will accordingly be evident that all pulling strain from the seat of tightly drawn up trousers may be relaxed, and by connecting the suspender ends 6 with the hooks 9 the trousers will still be securely supported. The wearer may thus sit in comfort while the suspenders are temporarily loosened, and this slack or looseness in the suspenders may be obtained without disturbing the position of the clamping slides or otherwise changing the normal adjustment of the suspenders to normally support the trousers as desired by the wearer. When the wearer again assumes a standing position the suspender ends 6 may be moved out of engagement with the hooks 9 and the tabs 5 again fastened in normal position, as will be readily understood.

For the purpose of securing additional security of connection between the suspender end 6 and hook 9, I may employ a second supplemental fastener. This consists of a bracket plate 11 carrying at its upper end a spring stud 12 for detachable engagement with the socket 7 and having its lower end forked and formed with a pair of spaced eyes 13. The eyes 13 receive and engage the suspender end 6 on opposite sides of its center and are adapted to lie on opposite sides of the hook 9, with which the suspender end 6 is engaged between said eyes. The supplemental fastener, when used, thus forms a permanent attachment to the suspender end 6 and acts as a supplemental hanger therefor, increasing the extent of the supporting bearing and the security of the connection. When the tab 5 is folded up and in normal position it will be observed that the fastener 9 is held and concealed between its folds, while the fastener 11 is detached from the socket 7 and is held by the suspender end 6 so as to also lie between the folds of the tab and to be concealed thereby. It is obvious, of course, that little or no change in the construction of the parts of the suspender will be required to permit of the use of the invention, thus enabling the supplemental fasteners to be applied to ordinary suspenders at small cost.

For the purpose of insuring a firm engagement between the hook 7 and the suspender end, the bill of the hook may be bent into substantially V-form, to provide a spring closure 14 and flaring entrance to the hook.

Having thus described my invention, what I claim is:

1. In an attachment for suspenders, the combination of a suspender strap, a tab secured at one end to the strap, coacting fastening members upon the respective ends of the tab for securing said tab in folded and loop forming position, a suspender end adapted to be held at a normal elevation in the bight of the folded tab, and means for supporting the suspender end at a lower ele-

vation directly from the free end of the tab when said end of the tab is released and the tab disposed in a depending position.

2. In an attachment for suspenders, the combination of a suspender strap, a tab secured at one end to the strap, coacting fastening members upon the respective ends of the tab for securing said tab in folded and loop forming position, a suspender end adapted to be held at a normal elevation in the bight of the folder tab, and a fastening member upon the suspended end engageable with the fastening member on the free end of the tab for supporting the suspender end at a lower elevation directly from the free end of the tab when said end of the tab is released and the tab disposed in a depending position.

3. In an attachment for suspenders, the combination with a suspender strap, a suspender end, a tab carried by the strap, and coacting fastening members upon the tab for securing it in folded and looped form to hold the suspender end at a normal elevation in the bight of the loop, of a hooked supplemental fastening member supported by the fastening member on the free end of the tab for supporting the suspender end at a lower elevation from such end of the tab when said tab is unfolded and extended.

4. In an attachment for suspenders, the combination with a suspender strap, a suspender end, a tab carried by the strap, and coacting fastening members upon the ends of the tab for securing it in folded and looped form to hold the suspender end in the bight of the loop at a normal elevation, of a fastening member held by the fastening member upon the free end of the tab for securing the suspender end at a lower elevation to said tab when said tab is unfolded and extended linearly from the strap, and a fastening member upon the tab and engageable with the last-named fastening members to additionally secure said suspender end to the free end of the tab.

5. In an attachment for suspenders, the combination with a suspender strap, a suspender end, a tab carried by the strap, and fastening members upon the ends of the tab adapted for interengagement to hold the tab folded and in looped form to receive and hold the suspender end, of a supplemental fastening member carried by the free end of the tab to detachably receive and support the suspender end when the tab is unfastened and extended, and a second supplemental fastening member carried by the suspender end and detachably engageable with the said supplemental fastening member and the fastening member upon the free end of the tab for additionally securing the suspender end to the let down tab.

6. In an attachment for suspenders, the combination with a suspender strap, a sus-

pender end, a tab carried by the suspender strap, interlocking stud and socket fastening members upon the ends of the tab for securing the tab in folded and loop forming 5 position, a fastening member held by the fastening member at the free end of the tab for detachably receiving and holding a suspender end, and a fastening member attach-

able to a suspender end and adapted for detachable engagement with the last named 10 fastening member for additionally securing the suspender end to the free end of the tab.

In testimony whereof I hereunto affix my signature.

WILLIAM EDWARD LANE.
